TORCH TIP ASSEMBLING TOOL

Alexander F. Jenkins, Baltimore, Md.

Original application July 31, 1940, Serial No. 348,888. Divided and this application September 11, 1942, Serial No. 458,022

3 Claims. (Cl. 29—68.2)

This invention relates to gaseous fuel burners and more particularly to blowtorches, and has for its principal object the provision of novel and improved means for constricting certain of the passageways in such torches—especially in the torch tips—to more effectively control the flow of gases therethrough, for providing openings leading into expansion chambers for the gases, and for streamlining the channels and restricted passageways of the torch to eliminate all burrs, roughness, or other obstacles which might obstruct or divert the smooth flow of the fluids, or give rise to eddy currents.

This application is a division of my co-pending application, Serial No. 348,888, filed July 31, 1940.

The invention in its preferred embodiments contemplates means for providing small tubular inserts having fine bores therein, within the passageways of the torch tips or of the injectors of welding torches. The inserts are preferably made of a harder, finer grained metal than that of which the torch tips or injectors proper are made, and one which is relatively non-corrosive and which may be machined smoothly without burring.

A primary object of the invention is to provide a novel and improved tool or implement adapted for the efficient and rapid insertion, seating, or embedding of these metal inserts in the tubular passageways of the torch tip. One of the features of the invention is the provision of a tool of this character which is provided with projecting elements adapted to engage the small tubular inserts and propel them through the passageways of the torch tip to their seats within the tip, and to obviate any difficulties attendant to the rapid and accurate application of the elements of the tool to the passageways. Novel means are provided for projecting the elements unequal distances from the main body portion of the tool so that they may be successively inserted in the orifices of the torch tip, the arrangement being such that the projection of the elements may be equalized when pressure is applied to the tool as the inserts are driven home.

Other objects and features of novelty will be apparent from the following specification when read in connection with the accompanying drawing in which several embodiments of the invention are illustrated by way of example.

In the drawing,

Figure 1 is a view in longitudinal section of the tool and of one end of a torch tip, taken on line 1—1 of Figure 3, showing the manner of insertion;

Figure 2 is a similar view, taken substantially on the line 2—2 of Figure 3, and showing the position of others of the projecting pins of the tool;

5 Figure 3 is a view in transverse section taken on line 3—3 of Figure 1; and

Figure 4 is a view in longitudinal cross-section taken substantially on the same line as Figure 1, but showing the positions of the tool and of the 10 inserts when the latter are driven home within the torch tip.

In the drawing, a partially completed torch tip with an unswaged forward end 10B is indicated generally by the reference numeral 10. This type of tip has been selected for illustrative purposes, only and it is understood that the invention in its broad aspects is not limited to application to this type of tip, but may be applied to torch tips of other kinds, to the injectors commonly used in cutting and welding torches, and in fact in many situations where it is necessary to force a plurality of small inserts simultaneously into a number of substantially parallel passageways or orifices. In the tip selected for illustration here-

25 in, the gas passageways 20 are provided with constricted inlet portions 27 leading from the oxygen groove 14. The short inserts 25 in this instance are provided with a single bore 26 which constitutes the mixing chamber. Identical openings

30 28 and 29 are provided in conjunction with each of the inserts 25 and passageways 20 to permit the heating gas from the groove 15 to the mixing chamber 26. In this example, the tubular inserts 25 abut the shoulders 40 which are formed 35 at the junctions of the passageways 20 and the restricted inlet openings 27, and extend a short distance into the bores 26 of the body of the tip. The fragmentary cross sectional view in Figure

40 4 shows the inserts 25 at the moment of seating against the shoulders 40 by means of the rods or pins of an applying tool which will be later described. At this point, the small tubular inserts 25 are disposed between the shoulder 40 and the cone 51 of these rods 50.

45 The method of forming and assembling these tips will now be described together with the novel and ingenious tool or implement employed in applying the inserts. The head 13 of the partially formed torch tip blank is completed so far

50 as its external configuration is concerned, the oxygen and heating gas grooves already having been formed therein. Also the central oxygen passageway 18 has been drilled axially of the tip and the passageways 20 have been formed by drilling from the forward end of the torch tip,

In this example, the maximum bores of the passageways 20 are terminated at the shoulder 40 and then the restricted passageway 21 is drilled from point 40 into the groove 14.

The next step is the insertion of the short tubular elements 25 or 25' into the bores 29 so as to firmly press or embed them within the rear ends thereof. The inserts are placed within the forward ends of the respective bores 20 as indicated in Figure 1, and in order to force the inserts through the bores to the rearward ends thereof a pressing or swaging tool such as that illustrated at 45 is employed.

The tool 45 comprises a driving head 47 which is cup-shaped, having an interior recess 48 therein. Within the outer portion of the recess 48 there is secured the plate 49 through which the rods 50 project. These rods are provided with tapered points 51 and enlarged heads 52. The plate 49 is provided with flared openings 54 through which the shanks of the rods 50 extend. The openings 54 are of varying depth, the inner ends of the flared openings being provided with shouldered abutment portions 53 against which the heads 52 are adapted to seat. The openings 54 are thus in effect countersunk with the countersunk portions thereof stepped so as to extend to various degrees of depth into the plate or block 49. As a matter of fact, one of the openings 54 need not be countersunk but the head 52 of the pin 50 associated therewith may rest directly upon the inner face of the plate 49 as indicated in the upper right-hand portion of Figure 1. The rods 50 are preferably of equal length but the stepped recesses into which the heads 52 are adapted to enter provide means for staggering the rods so that the points 51, when all of the rods are extended from the head 47, occupy different transverse planes. This permits the successive introduction of the points 51 into the respective passageways 20, of which there are usually four in cutting torch tips of this type as shown in Figure 3. It will be seen that this arrangement greatly facilitates the introduction of the points of the tool; each successive point being guided individually into its proper opening.

When all of the points are applied, the head 47 of the tool is moved toward the torch tip whereupon the heads 52 of the several rods 50 abut the rear wall of the recess 48 as in Figure 4. Continued movement of the tool 45 toward the torch tip by suitable means such as a press, serves to force the inserts 25, 25' through the passageways 20 until they are seated at the proper point at the rear ends of the passageways. In the case of the tip illustrated, a shoulder 40 provides a stop abutment for the inserts. Upon the termination of the movement of the inserts, the tapered points 51 of the tool 45 serve to swage the forward ends of the inserts 25 toward the walls of the passageways 20 and securely and permanently embed them within the torch front end 10B of the tip. The tool 45 is then withdrawn and the tip blank is swaged in order to provide the proper taper, and then the oxygen passageway 18 and the heating gas passageways 20 may be rebored at their forward ends. The

transverse ducts 28, 29 are then drilled to provide communication between the gas supply groove 15 and the mixing chambers or bores 26, 26' in the inserts.

It is understood that various changes and modifications may be made in the embodiments illustrated and described herein without departing from the scope of the invention as defined by the following claims.

Having thus described the invention what is claimed as new and desired to be secured by Letters Patent is:

1. A tool for assembling torch tips having a plurality of longitudinal bores therein, into which are firmly seated tubular inserts; said tool comprising a head, a plurality of pins projecting from said head and movably carried thereby, said pins all being of equal length, lost motion connections between said head and said pins so constructed and arranged that the movement of said pins with respect to said head toward the work is limited to different distances and a common abutment on said head lying in a single transverse plane and providing a backstop for said pins, whereby the outer ends of said pins may be individually and successively introduced into the several bores of the torch and then forced equally therein by the application of pressure to the head.

2. A tool for assembling torch tips having a plurality of longitudinal bores therein, into which are firmly seated tubular inserts; said tool comprising a hollow head, a plurality of headed pins projecting from said head, said pins being all of equal lengths, said head comprising a forwardly disposed plate having openings therein for the shanks of said pins, each of said openings being countersunk to a different depth, whereby when the pins are extended the heads of the pins enter said countersunk portions of the openings, and an abutment portion on said head occupying a single plane and limiting the retractive movement of said pins, whereby the outer ends of said pins may be individually and successively introduced into the several bores of the torch and then forced equally therein by the application of pressure to the head.

3. A tool for assembling torch tips having a plurality of longitudinal bores therein, into which are firmly seated tubular inserts; said tool comprising a hollow head, a plurality of headed pins projecting from said head, said head comprising a forwardly disposed perforated wall through which the pins extend, the openings in the wall being of sufficient diameter to accommodate the shanks of the pins, surfaces adjacent the rear of said perforated wall to engage and stop the heads of the pins when the pins are extended, a rear wall on said head having surfaces against which the heads of the pins abut when the pins are retracted, the distances between the abutment surfaces of the two walls in the case of each of said pins being different from those of the others to allow said pins to move different relative distances.

ALEXANDER F. JENKINS.
